UNITED STATES PATENT OFFICE.

THOMAS J. LEWIS, OF NEW YORK, N. Y.

HAND BAG WITH COSMETIC FOLDERS.

Application filed September 8, 1928. Serial No. 304,670.

The object of the present invention is to provide a hand bag, in appearance generally similar to bags customarily carried by women for daily use, and which comprises 5 as an integral part a cosmetic folder so arranged that when the folder is withdrawn from the bag and spread out with the cosmetic jars or other holders exposed, it is tied to the bag and the latter prevents the holder 10 from being vibrated from a polished shelf or the like, as when the device is being used on a moving conveyance, for example in the ladies' room of a Pullman coach, etc.

The invention will be described with reference to the accompanying drawings, in which—

Figure 1 is a plan view of the device with the folder drawn outwardly for position and use;

Figure 2 is a plan view of the device closed;

Figure 3 is a transverse section on the line 3—3, Fig. 2, and

Figure 4 is an end view of the device.

Referring to the drawings 1 indicates the body of the bag having a cover or flap 2, a strap 3 being provided, the strap having at one end a loop 3^x and at the opposite end a buckle 4 through which the loop may be passed, providing a convenient means of holding the bag in that the hand may be passed through the loop and the bag held at the base thereof by the hand, insuring that the flap or cover will remain in closed position. The bag is preferably made of soft material, as for example leather. It is formed with a rigid two-part frame 5, 5^x, the two parts of the frame being hinged at 6. One member of the frame is provided 40 with a catch device 7 and the other member with a co-acting catch device 8. A short finger strap 9 may be carried by frame member 5 as a convenient aid to the unlatching of the two frame members. In the present 45 instance there is located within the bag a purse 10 having a customary form of spring-and-ball catch 11.

Intermediate frame member 5^x and the flap is a compartment which extends to the base of the bag. At the end of this compartment is secured a broad flexible band 12 which preferably is made of the same mate-

rial as the lining 2^x of the flap. Secured to this band is a boarded sheet 13 preferably covered with the same material as the outer covering of the bag 1, and secured to the boarded sheet 13 is a flexible cover 14 having a snap fastening member 15 adapted to coact with a snap fastening member 15^x, the latter being disposed on top of a loop device 16. The loop device is sewn or otherwise firmly secured to the relatively stiff boarded member 13, and affords a plurality of loops for the reception of bottles or jars of cosmetics, as indicated by the numerals 65 17. Supplementary loop devices 18 and 19 may hold additional cosmetic preparations.

When the soft cover 14 is moved back upon the boarded member and is snapped in position, the said member may be pushed down into the compartment rearwardly of frame member 5^x, band 12 folding into position within the compartment, and thereafter the primary cover flap 2 of the bag may be folded over to permit closing of the bag by 75 the strap and buckle device.

As seen in Figure 2, the bag with its cover affords a broad support for the boarded member with the supplementary cover 14, and notwithstanding the boarded 80 member is an integral part of the bag, the cosmetics are placed, as to their containers, in a most convenient position for utilization.

It will be noted that glass bottles or other frail containers may be safely used in the 85 device inasmuch as at one side of the case they are protected by the folds of material secured to the frame members 5, 5^x, and in addition the material comprising the inner purse, whereas at the opposite face the said 90 containers are protected by the stiff boarded member 13 in addition to the rear wall of the bag.

It will be understood that modifications may be made in the form and arrangement 95 of the elements comprising the device, without departing from the spirit of the invention, what I claim and desire to secure by Letters Patent being as follows:—

1. A hand bag comprising a hinged frame 100 covered with flexible material and forming a major compartment member having opposed walls, a cover flap, a supplemental compartment provided intermediate the said

walls and the cover flap, a boarded carrier disposed in the supplemental compartment, a flexible band connecting the boarded member and the bag, and adapted to be folded 5 within the supplemental compartment, holding-devices carried by the boarded member for a plurality of cosmetic jars, the boarded member being disposed within the supplemental compartment in such manner that 10 the cosmetic jars are shielded on one side by the boarded member and a wall of the bag, and at the opposite side by the opposed walls of the bag.

2. A hand bag comprising a hinged frame 15 covered with flexible material and forming a major compartment member having opposed walls, an inner purse secured within the compartment, a cover flap, a supplemental compartment provided intermediate

the said walls and the cover flap, a boarded 20 carrier disposed in the supplemental compartment, a flexible band connecting the boarded member and the bag, and adapted to be folded within the supplemental compartment, holding-devices carried by the 25 boarded member for a plurality of cosmetic jars, a flexible cover carried by the boarded member and means for holding the cover in position to overlap said jars, the boarded member being disposed within the supplemental compartment in such manner that the cosmetic jars are shielded on one side by the boarded member and a wall of the bag, and at the opposite side by the opposed walls of the bag and said inner purse.

In testimony whereof, I have signed my name to this specification.

THOMAS J. LEWIS.
